STACKABLE REINFORCED CONCRETE POST FOR VARIOUS OUTDOOR APPLICATIONS

This invention claims priority to application Ser. No. 15/648,641 filed Jul. 13, 2017, and is a continuation in part of that application.

BACKGROUND OF THE INVENTION

The invention pertains to concrete post design and construction that can be used with other fencing materials. This invention has comparable or potentially a longer life span than the traditional wooden post. Also, it should be an excellent replacement to the traditional wooden post, as timber is getting scarce. The stackable concrete post can potentially be installed with less man power since the post is made up of modular elements. The applications of this invention include standard privacy fencing, and barbed and woven wire fencing.

BRIEF SUMMARY OF THE INVENTION

The stackable reinforced concrete post consists of a concrete pylon base and multiple concrete modules, that are stacked vertically to form a post that can be used to erect fencing. The concrete pylon base and concrete module are reinforced using a galvanized wire cage within the concrete. The pylon base and modules have specifically designed holes where the rebar is inserted. Epoxy and/or anchoring cement is used to fill in the space in the holes with the rebar inserted into for permanently anchoring the rebar. Mortar or waterproof silicone is applied between the stacking of the units to prevent any possible damage to the joint due to freezing precipitation.

BRIEF DESCRIPTION OF DRAWINGS

FIG. 1 shows a superior view of a module.

FIG. 2 shows a posterior view of the module in FIG. 1. FIG. 3 shows a lateral view of a side of the module of FIG. 1.

FIG. 4 shows a superior view of the inside of the module of FIG. 1, specifically the galvanized wire cage within the module.

FIG. 5 shows an internal posterior view of the module of FIG. 1, specifically the galvanized wire cage and the holes where rebar is to be inserted.

FIG. 6 shows an internal lateral view of the module of FIG. 1, providing views of the galvanized wire cage and the holes where rebar is to be inserted.

FIG. 7 shows a superior view of the module of FIG. 1, pointing out a bolt for a privacy or rail fence application.

FIG. 8 shows a posterior view of the module of FIG. 1, pointing out the bolt for a privacy or rail fence application.

FIG. 9 shows a lateral view of the module of FIG. 1, pointing out the bolt for a privacy or rail fence application.

FIG. 10 shows a posterior view of the module of FIG. 1, pointing out a hole prior to the insertion of the bolt.

FIG. 11 shows an internal lateral view of the module of FIG. 1 with the bolt in place.

FIG. 12 shows a superior view a module, with an emphasis on the two holes where the rebar is to be inserted.

FIG. 13 shows a posterior view of the module of FIG. 12, showing a notch where the wire or barbed wire fencing lays in.

FIG. 14 shows a lateral view of the module of FIG. 12 with a view of the notch for the fencing.

FIG. 15 shows an internal lateral view of the module of FIG. 12 to provide the position of the galvanized wire cage in relation to the notch in a post.

A concrete pylon base is depicted in FIGS. 16-19, as follows:

FIG. 16 shows a superior view of the a base of the post.

FIG. 17 shows a posterior view of the pylon base of the post.

FIG. 18 shows a lateral view of the pylon base of the post.

FIG. 19 shows an internal superior view of the pylon base of the post, pointing out the galvanized wire cage within it.

FIG. 20 shows an inferior view of the base of the pylon base of the post.

FIG. 21 shows an internal posterior view of the pylon base of the post, with the galvanized wire cage within it and the holes where the rebar is to be inserted.

FIG. 22 shows an internal lateral view of the pylon base of the post, with the galvanized wire cage within it and the holes where the rebar is to be inserted.

FIG. 23 shows this invention used in standard privacy fencing.

FIG. 24 shows this invention used in barbed wire fencing.

FIG. 25 shows this invention used in woven wire fencing.

FIG. 26 shows the construction of the post. This invention consists of a pylon base and multiple modules such as 9 more or less modules. Please note, the picture does not show all the modules.

FIG. 27 shows another view of one of another module used in the post.

FIG. 28 shows another view of the module in FIG. 27 showing the wire cage in the module.

FIG. 29 shows another posterior view of the module in FIG. 27.

FIG. 30 shows an interior view of the module of FIG. 27 showing the wire cage.

FIG. 31 is another interior view of the module of FIG. 27.

FIG. 32 is a side view of the module of FIG. 27, showing a notch.

FIG. 33 is a side view of the module of FIG. 27 showing concrete anchors inserted in the module.

FIG. 34 is a side view of the module of FIG. 27, showing holes for the concrete anchors.

FIG. 35 is an interior view of the post, showing the wire cage and rebar.

FIG. 36 is a side view of the post connected to fencing.

DETAILED DESCRIPTION OF THE INVENTION

The invention is a post. Each post consists of a concrete pylon base and 9 or more or less concrete modules. Please see FIGS. 23, 24, and 25 to get an idea what the post would look like.

The concrete pylon base and the modules are made out of cement, reinforced by a galvanized wire cage within the cement, and formed using a mold. The pylon base and the modules have specifically designed holes where the rebar is to be inserted; in addition, the modules have specific notch where the barbed and woven wire sit on. Please see FIGS. 16-22 for the position of the wire cage, the shape, and the dimension of the pylon base, and FIGS. 1-15 for the modules. The dimensions given are important to the success of the invention.

To build a post, a pylon base and multiple modules are stacked vertically, reinforced by rebar, anchoring cement and waterproof silicone. Below are the steps to build a post:

Dig a hole in the ground big and tall enough to bury the units that sit below the ground level (a pylon base, a module and half of a module). See FIGS. 23, 24, and 25 for the size of the hole needed. To determine the depth in which to place the post, determine the height that the fence is desired to be from the ground. The post should be placed one third of the height of the fence into the ground.

Lower a pylon base into the ground. On the top side of the pylon base, fill in the rebar holes with epoxy or anchoring cement and insert the rebar into the holes.

Apply mortar or waterproof silicone on top of the pylon base.

Prepare the module that is to be stacked on top of the pylon base by filling in the module's bottom holes with epoxy or anchoring cement.

Stack the module on top of the pylon base by inserting the rebar that is sticking out from the pylon base top to the bottom holes of the module.

Apply pressure to compress the mortar to a $\frac{3}{8}$ -inch gap. Level the post from the top, front, back and sides. Trowel off the excess mortar, if any. If waterproof silicone is used, apply pressure to connect the modules and/or pylon base and remove any excess waterproof silicone.

We now have a post consisting the pylon base and one module stacked vertically.

On the top side of the post, fill in the rebar holes with epoxy or anchoring cement and insert the rebar into the holes.

Apply mortar or anchoring cement on the top side of the post.

Prepare the next module that is to be stacked on top of the post by filling in the module bottom holes with epoxy or anchoring cement.

Stack the module on top of the post by inserting the rebar that is sticking out on the top side of the post to the bottom holes of the module.

Apply pressure to compress the mortar to a $\frac{3}{8}$ -inch gap. Level the post from the top, front, back and sides. Trowel off the excess mortar, if any. If waterproof silicone is used, apply pressure to connect the modules and/or pylon base and remove any excess waterproof silicone.

We now have a post consisting a pylon base and 2 modules stacked vertically.

Do the next stacking by repeating steps 7-11 until all the modules (9 or more or less) have been completed. Please see FIG. 26 as a reference.

FIGS. 1, 2, 3, 4, 5, 6, depict top, front, and side views of a module and its overall dimensions, the wire cage within the module, and the holes where the rebar would be inserted.

Regarding FIG. 1, a module 100 to be used in the post is shown. The dimension at 101 is $\frac{3}{4}$ inches, the dimension at 102 is $4\frac{1}{2}$ inches, the dimension at 103 is $\frac{3}{4}$ inches, the dimension at 104 is 6 inches, the dimension at 105 is 2 inches, the dimension at 106 is 2 inches, the dimension at 107 is 2 inches, the dimension at 108 is 6 inches, the dimension at 109 is 5 inches, the dimension at 110 is 1 inch, and the angle at 111 is 54 degrees.

FIG. 2 is a posterior view of the module in FIG. 1. Regarding FIG. 2, the dimension at 201 is 9 inches.

FIG. 3 shows a lateral view of a side of the module of FIG. 1. Regarding FIG. 3, the dimension at 301 is 5 inches. The dimension 302 is 1 inch.

FIG. 4 shows a superior view of the inside of the module of FIG. 1, specifically the galvanized wire cage within the

module. Regarding FIG. 4, the cage 401 is a 16 ga (16 gauge), one inch by one inch galvanized wire cage.

FIG. 5 shows an internal posterior view of the module of FIG. 1, specifically the galvanized wire cage and the holes where rebar is to be inserted. Regarding FIG. 5, the cage 501 is a 16 ga (16 gauge) 1 inch by 1 inch galvanized wire cage. The two holes 502 for rebar are $\frac{3}{4}$ inches by 9 inches. The dimension at 503 is 2 inches. The dimension at 504 is 2 inches. The dimension at 505 is 2 inches. The dimension at 506 is 3 inches. The dimension at 507 is 3 inches. The dimension at 508 is 3 inches.

FIG. 6 shows an internal lateral view of the module of FIG. 1, providing views of the galvanized wire cage and the hole where rebar is to be inserted. As this is a side view of FIG. 5, only one hole 502 is shown as the holes from FIG. 5 are lined up behind each other. Regarding FIG. 6, the cage 601 is a 16 gauge 1 inch by 1 inch galvanized wire cage. The hole 502 for rebar is $\frac{3}{4}$ inches by 9 inches.

FIGS. 7, 8, 9, 10, 11 illustrate the socket flat head screw used for attaching different fencing materials to the modules. The top, front, and side views of the module demonstrate the hole's position and dimension and the size of the socket flat head screw.

FIG. 7 shows a superior view of the module of FIG. 1, pointing out a bolt for privacy fence or rail fence application. Regarding FIG. 7, the dimension 701 is 6 inches. The dimension 702 is $\frac{3}{4}$ inches. The dimension 703 is 4 and $\frac{1}{2}$ inches. The dimension 704 is $\frac{3}{4}$ inches. The dimension 705 is 1 inch. The dimension 706 is 5 inches. The dimension 707 is 2 inches. The dimension 708 is 2 inches. The dimension 709 is 2 inches. The dimension 710 is 6 inches. The screw 711 is a $\frac{3}{8}$ -16 by 2 inch socket flat head screw.

FIG. 8 shows a posterior view of the module of FIG. 1, pointing out the bolt for barbed wire fence and woven wire fence application. Regarding FIG. 8, the dimension 801 is 9 inches, and the screw 711 is a $\frac{3}{8}$ -16 by 2 inch socket flat head screw.

FIG. 9 shows a lateral view of the module of FIG. 1, pointing out the bolt for barbed wire fence and woven wire fence application. Regarding FIG. 9, the dimension 901 is 2 inches, the dimension 902 is 7 inches. The dimension 903 is 5 inches. The dimension 904 is 1 inch.

FIG. 10 shows a posterior view of the module of FIG. 1, pointing out a hole prior to the insertion of the bolt. Regarding FIG. 10, the hole 1001 is a $\frac{7}{16}$ by 1 and $\frac{5}{8}$ inch hole. The hole 1001 is for a bolt to be inserted. The dimension 1002 is 2 and $\frac{3}{4}$ inches. The dimension 1003 is $\frac{1}{2}$ inches. The dimension 1004 is 2 and $\frac{3}{4}$ inches.

FIG. 11 shows an internal lateral view of the module of FIG. 1 with the bolt in place. Regarding FIG. 11, the cage 1101 is a 16 ga 1 inch by 1 inch galvanized wire cage. The dimension 1102 is 4 and $\frac{3}{8}$ inches. The dimension 1103 is 1 and $\frac{5}{8}$ inches. The dimension 1104 is 1 and $\frac{3}{4}$ inches. The dimension 1105 is $\frac{1}{2}$ inch. The dimension 1106 is 6 and $\frac{3}{4}$ inches.

FIG. 12 illustrates the two holes where the rebar would be inserted. FIGS. 13, 14, 15 illustrate notch where a barbed wire or woven wire fence is secured on.

FIG. 12 shows a superior view a module 1200 that is an embodiment of the module of FIG. 1, with an emphasis on the two holes where the rebar is to be inserted. Regarding FIG. 12, the dimension 1201 is 6 inches. The dimension 1202 is $\frac{3}{4}$ inches. The dimension 1203 is 4 and $\frac{1}{2}$ inches. The dimension 1204 is $\frac{3}{4}$ inches. The dimension 1205 is 1 inch. The dimension 1206 is 5 inches. The dimension 1207

is 2 inches. The dimension **1208** is 2 inches. The dimension **1209** is 2 inches. The dimension **1210** is 6 inches. The angle **1211** is 54 degrees.

FIG. 13 shows a posterior view of the module of FIG. 12, showing a notch where the wire or barbed wire fencing lays in. Regarding FIG. 13, the dimension **1301** is 9 inches. The dimension **1302** is 1 and $\frac{1}{2}$ inches. The dimension **1303** is 1 and $\frac{1}{2}$ inches. The dimension **1304** is 6 inches. The dimension of a notch **1305** is 1 and $\frac{1}{2}$ inches by $\frac{3}{4}$ inches.

FIG. 14 shows a lateral view of the module of FIG. 12 with a view of the notch for the fencing. Regarding FIG. 14, dimension **1401** is $\frac{3}{4}$ inches, dimension **1402** is 5 and $\frac{1}{4}$ inches. Dimension **1403** is 5 inches. Dimension **1404** is 1 inch.

FIG. 15 shows an internal lateral view of the module of FIG. 12 to provide the position of the galvanized wire cage in relation to the notch in a post. Regarding FIG. 15, a notch **1501** is of dimensions 1 and $\frac{1}{2}$ inches by $\frac{3}{4}$ inches. Cage **1502** is a 16 ga 1 inch by 1 inch galvanized wire cage. The dimension at **1503** is 5 and $\frac{1}{4}$ inches. The dimension **1504** is $\frac{3}{4}$ inches. The dimension **1505** is 1 and $\frac{1}{2}$ inches. The dimension **1506** is 1 and $\frac{1}{2}$ inches. The dimension **1507** is 6 inches.

FIGS. 16, 17, 18, 19, 20, 21, 22 show a pylon base with its dimensions, the wire cage within the unit, and the holes where the rebar would be inserted.

FIG. 16 shows a superior view of a base **1600** of the post. Regarding FIG. 16, the dimension **1601** is 6 inches. The dimension **1602** is 1 inch. The dimension **1603** is 5 inches. The dimension **1604** is 1 inch. The dimension **1605** is 1 inch. The dimension **1606** is 5 inches. The dimension **1607** is 2 and $\frac{1}{2}$ inches. The dimension **1608** is 2 inches. The dimension **1609** is 2 and $\frac{1}{2}$ inches. The dimension **1610** is 7 inches. The angle at **1611** is 45 degrees.

FIG. 17 shows a posterior view of the pylon base shown in FIG. 16 of the post. Regarding FIG. 17, the dimension **1701** is 1 foot and 7 inches. The dimension **1702** is 7 inches. The dimension **1703** is 10 inches.

FIG. 18 shows a lateral view of the pylon base shown in FIG. 16 of the post. Regarding FIG. 18, the dimension **1801** is 1 foot and 7 inches. The dimension **1801** is 5 inches. The dimension **1802** is 1 inch. The dimension **1803** is 8 inches. The dimension **1804** is 1 inch.

FIG. 19 shows an internal superior view of the pylon base shown in FIG. 16 of the post, pointing out the galvanized wire cage within it. Regarding FIG. 19, cage **1901** is a 16 ga 1 inch by 1 inch galvanized wire cage.

FIG. 20 shows an inferior view of the base of the pylon base shown in FIG. 16 of the post. Regarding FIG. 20, dimension **2001** is 9 inches. Dimension **2002** is 10 inches. Dimension **2003** is 8 inches. Dimension **2004** is 1 inch. Dimension **2205** is 1 inch. Dimension **2006** is 8 inches. Dimension **2007** is 1 inch.

FIG. 21 shows an internal posterior view of the pylon base shown in FIG. 16 of the post, with the galvanized wire cage within it and the holes where the rebar is to be inserted. Regarding FIG. 21, holes **2101** are $\frac{1}{2}$ inch by 3 and $\frac{11}{16}$ inches for rebar insertion. Cage **2102** is a 16 ga 1 inch by 1 inch galvanized wire cage. Dimension **2103** is 2 and $\frac{1}{2}$ inches. Dimension **2104** is 2 inches. Dimension **2105** is 2 and $\frac{1}{2}$ inches. Dimension **2106** is 3 inches. Dimension **2107** is 1 foot and 4 inches. Dimension **2108** is 10 inches.

FIG. 22 shows an internal lateral view of the pylon base shown in FIG. 16 of the post, with the galvanized wire cage within it and the holes where the rebar is to be inserted. Regarding FIG. 22, hole **2201** is a $\frac{1}{2}$ inch by 3 and $\frac{11}{16}$ inch hole for rebar. Cage **2202** is a 16 ga 1 inch by 1 inch

galvanized wire cage. Dimension **2203** is 9 inches. Dimension **2204** is 3 inches. Dimension **2205** is 3 inches.

FIG. 23 depicts an application of this invention for privacy fencing. It shows the drop-in anchors and the socket flat heads that are used to attach the boards to post. Shown at **2300** is the post that is the invention. Regarding FIG. 23, screw **2301** is a $\frac{3}{8}$ -16 by 2 inch socket flat head screw. Anchor **2302** is a $\frac{3}{8}$ inch by 1 and $\frac{5}{8}$ inches anchor. Hole **2303** is a $\frac{7}{16}$ inch by 1 and $\frac{5}{8}$ inch hole. Module **2304** is a standard top fence module. Module **2305** is a standard middle post module. Module **2306** is a standard middle fence module. Mortar **2307** is applied between modules, and compressed to $\frac{3}{8}$ inches. Dimension **2308** is 2 inches by 4 inches. Dimension **2309** is 4 and $\frac{5}{8}$ inches. Dimension **2310** is 9 inches. Dimension **2311** is 19 inches. Dimension **2312** is 33 and $\frac{3}{8}$ inches below ground level. Module **2313** is a standard pylon module. Plank **2314** is a 1 inch by 6 inch plank. Plank **2315** is a 2 inch by 6 inch plank.

FIG. 24 depicts an application of this invention for a barbed wire fence. It shows notch where the barbed wire sits on, which is secured to the modules with tie-backs. Shown at **2400** is an embodiment of the post that is the invention.

Regarding FIG. 24, mortar **2401** is applied between modules (such as **2404**, **2405**, **2407**) and compressed to $\frac{3}{8}$ inches. Barbed wire **2402** is inserted into notches **2403**. The notches **2403** are 1 and $\frac{1}{2}$ by $\frac{3}{4}$ inches in dimension. Module **2404** is a standard top wire module. Module **2405** is a standard middle wire module. Tie **2406** is a 12.5 ga galvanized tie. The tie **2406** can affix the barbed wire **2402** to a notch **2403**. Module **2407** is a standard pylon module. Dimension **2408** is 33 and $\frac{3}{8}$ inches below ground level. Dimension **2409** is 4 and $\frac{5}{8}$ inches. Dimension **2410** is $\frac{3}{8}$ inches. Dimension **2411** is 9 inches. Dimension **2412** is $\frac{3}{8}$ inches. Dimension **2413** is 19 inches.

FIG. 25 depicts an application of the post **2400** that is this invention for woven wire fence. It shows a notch **2503** or notch where the woven wire fence can be attached to the modules with tie-backs.

Regarding FIG. 25, mortar **2501** is applied between modules (such as **2504**, **2505**, and **2507**). A woven wire fence **2502** is 10 ga. A notch **2503** is 1 and $\frac{1}{2}$ inches by $\frac{3}{4}$ inches. Module **2504** is a standard top wire module. Module **2505** is a standard middle wire module. Tie **2506** is 12.5 gauge galvanized tie, which is used to tie-back the fence **2502** into a notch **2503**. Module **2507** is a standard pylon module. Dimension **2508** is 33 and $\frac{3}{8}$ inches below ground level. Dimension **2509** is 4 and $\frac{5}{8}$ inches. Dimension **2510** is $\frac{3}{8}$ inches. Dimension **2511** is 9 inches. Dimension **2512** is $\frac{3}{8}$ inches. Dimension **2513** is 19 inches.

FIG. 26 depicts an application of this invention for board rail fence. It shows the drop-in anchors and the socket flat heads that are used to attach the boards to the post.

Regarding FIG. 26, a dimension of board **2601** is 2 inches by 6 inches. Screw **2602** is a $\frac{3}{8}$ -16 by 2 inch socket flat head screw. Dimension of board **2603** is 2 inches by 4 inches. Mortar **2604** is applied between modules (such as **2606**, **2609**, **2613**). Anchor **2605** is a $\frac{3}{8}$ inch by 1 and $\frac{5}{8}$ inch anchor that can be dropped into a hole **2610**. Module **2606** is a standard middle post module. Rebar **2608** of $\frac{3}{8}$ inch by 6 inch dimension is connected to modules (such as **2606**, **2609**, **2613**) with epoxy. Module **2609** is a standard middle fence module. Hole **2610** is a $\frac{7}{16}$ inch by 1 and $\frac{5}{8}$ inch hole. Hole **2612** is a $\frac{1}{2}$ inch by 3 and $\frac{11}{16}$ inches. The hole **2612** receives rebar **2608** and the rebar is connected to the hole **2612** with epoxy. Module **2613** is a standard pylon module.

FIG. 27 shows another view of one of another module 2700 used in the post that is this invention. Regarding FIG. 27, dimension 2701 is 6 inches. Angles 2702 and 2703 are 54 degrees. Dimension 2704 is 5 inches. Dimension 2705 is 2 inches. Hole 2706 is $\frac{3}{4}$ inches in size, and of 9 inches in length. Dimension 2707 is 2 inches. Dimension 2708 is 2 inches. Dimension 2709 is 6 inches.

FIG. 28 shows another view of the module in FIG. 27 showing the wire cage in the module. Regarding FIG. 28, cage 2801 is 16 ga 1 inch by 1 inch galvanized wire cage.

FIG. 29 shows another posterior view of the module in FIG. 27. Regarding FIG. 29, dimension 2901 is 9 inches. Dimension 2902 is 6 inches.

FIG. 30 shows an interior view of the module of FIG. 27 showing the wire cage. Regarding FIG. 30, Hole 3001 is $\frac{3}{4}$ inches by 9 inches, and is a hole for rebar (such as 2608, FIG. 26). Cage 3002 is a 16 ga 1 inch by 1 inch wire cage. Hole 3003 is a $\frac{3}{4}$ inch hole. Midpoint 3004 of the hole 3003 is $\frac{3}{16}$ inches from an exterior edge 3005 of the hole 3003.

FIG. 31 is another interior view of the module of FIG. 27. Regarding FIG. 31, holes 3103, 3105, 3106, and 3107 are $\frac{3}{16}$ inch holes. A center hole 3108 is a $\frac{3}{4}$ inch hole. Dimension 3102 from a $\frac{3}{16}$ hole (3103, 3105, 3106, and 3107) to an edge 3110 is 1 inch. Distance from $\frac{3}{16}$ holes 3103, 3105 to the center hole 3108 is 1 inch. Distance from $\frac{3}{16}$ holes 3106 and 3107 to center hole 3111 is 1 inch. The center holes 3108 and 3111 are 2 inches apart. Module 3100 has length 3112 of 9 inches. Notch 3101 has a width of 3 and $\frac{3}{4}$ inches with length of $\frac{3}{4}$ inches. Distance 3109 from hole 3105 and hole 3107 to the bottom 3113 of the notch 3101 is 1 inch.

FIG. 32 is a side view of the module of FIG. 27, showing a notch. Regarding FIG. 32, Dimension 3201 is 6 inches. Dimension 3202 is 6 inches. Notch dimension 3204 is 3 and $\frac{3}{4}$ inches. Notch dimension 3203 is $\frac{3}{4}$ inches. As an example, a 2 inch by 4 inch board can rest in the notch 3205.

FIG. 33 is a side view of the module of FIG. 27 showing concrete fasteners inserted in the module. Regarding FIG. 33, A first concrete fastener 3312 and a second concrete fastener 3301 are seen inserted into a module 3308. The fasteners 3301, 3312 are 3 and $\frac{3}{4}$ inch by $\frac{1}{4}$ inch phillips head concrete fasteners. The concrete fasteners 3301, 3312 are at a depth 3302 of 2 and $\frac{1}{4}$ inches into the concrete module 3308 if the fasteners are connected to a 2 inch by 4 inch fence board. The first concrete fastener 3312 is at a distance 3307 of 3 and $\frac{1}{4}$ inches below a top 3309 of the module. The second concrete fastener 3301 is a distance 3306 of 1 inch below the first concrete fastener 3312. A notch 3310 is in the module 3308, with a width 3303 of $\frac{3}{4}$ inches and a height 3311 of 3 and $\frac{1}{4}$ inches. The second concrete fastener 3301 is a distance 3305 of 1 inch above the bottom 3310 of the notch 3308. The fasteners 3301, 3312 just out a distance 3304 of $\frac{3}{4}$ inches out of the module 3308.

FIG. 34 is a side view of the module of FIG. 27, showing holes for the concrete fasteners. Regarding FIG. 34, the module 3414 is shown with holes 3409, 3410, 3407, and 3408. The holes (3409, 3410, 3407, and 3408) are $\frac{3}{16}$ inch holes, with depth of 2 and $\frac{1}{4}$ inch depth. The holes 3409 and 3410 are a distance 3412 of 1 inch from an edge 3415 of the module 3414. The holes 3409 and 3410 are a distance 3411 of 1 inch from each other. The hole 3410 is a distance 3413 of 1 inches from a bottom 3401 of the notch 3415. The bottom 3401 of the notch 3415 can support a 2 inch by 4 inch board 3405.

FIG. 35 is an interior view of an embodiment of the post that is this invention 3500, showing the wire cage and rebar. Regarding FIG. 35, the post 100 is shown with eight

modules (top module not shown) (3501, 3502, 3503, 3504, 3505, 3506, 3507, and 3508) on top of a base module 3509. Two $\frac{3}{8}$ inch rebar 3510 and 3511 are shown from the top module 3508 into the base module 3509. The rebar 3510 is placed into the $\frac{3}{4}$ inch hole 3512. The rebar 3511 is placed into the $\frac{3}{4}$ inch hole 3513. A top inch 3514 of the top module 3508 is composed of anchoring cement and seals the rebar 3510 and 3511 from weather. Each module (3501, 3502, 3503, 3504, 3505, 3506, 3507, and 3508) has a bead of transparent waterproof silicone between the module and an adjoining module ensure sealing between the modules from weather. The rebar 3510 and 3511 can be sealed by anchoring cement 2 hours at 2000 psi, and 30 days at 7000 psi, with the anchoring cement poured into both holes 3512, 3513. The total height of the post 100 is 80 inches, with the base module 3509 18 inches in height and the other eight modules module (3501, 3502, 3503, 3504, 3505, 3506, 3507, and 3508) 9 inches in height.

FIG. 36 is a side view of the post 3500 (FIG. 35) connected to fencing. Regarding FIG. 36, shown are 2 inch by 4 inch boards (3601, 3602, 3603) attached to the post 100 with cedar fencing boards (3604 and 3605).

The invention claimed is:

1. A stackable concrete post comprising:
a concrete pylon base,
wherein the concrete pylon base has two tapered edges
from top to bottom, with the bottom of the concrete
pylon base wider than the top of the concrete pylon
base,
wherein the concrete pylon base has two tapered edges
from one side of the top of the concrete pylon base to
another side of the top of the concrete pylon base;
wherein the concrete pylon base has a top surface end that
is completely flat to allow mating of vertical stacking of
multiple concrete modules to the completely flat top
surface of the concrete pylon base;
wherein the concrete pylon base has a galvanized wire
cage within the concrete pylon base,
wherein the galvanized wire cage within the concrete
pylon base is made of 16 gauge wire and is a one inch
by one inch galvanized wire cage;
multiple concrete modules comprised of cement that are
stacked vertically onto the concrete pylon base,
wherein the multiple concrete modules include exactly
two $\frac{3}{4}$ inch diameter by 9 inch length holes within each
of the multiple concrete modules for rebar,
wherein each of the exactly two $\frac{3}{4}$ inch diameter by 9 inch
length holes are vertical holes;
wherein each of the exactly two $\frac{3}{4}$ inch diameter by 9 inch
length holes are two inches from each other and $2\frac{1}{2}$
inches from a side of each of the multiple concrete
modules;
wherein each of the multiple concrete modules, other than
the concrete pylon base, are of equal size;
a single rebar inserted within each of the exactly two $\frac{3}{4}$
inch diameter by 9 inch length holes within each of the
multiple concrete modules, wherein each of the single
rebar extends from a top one of the multiple concrete
modules into the concrete pylon base;
anchoring cement inserted within the $\frac{3}{4}$ inch diameter by
9 inch length holes within each of the multiple concrete
modules;
waterproof silicone inserted between one of the multiple
concrete modules and another one of the multiple
concrete modules;

wherein the multiple concrete modules are reinforced with a galvanized wire cage inside each of the multiple concrete modules;

wherein the galvanized wire cage inside each of the multiple concrete modules is a 16 gauge one inch by one inch wire cage;

wherein there is vertical stacking of modules on the concrete pylon base;

wherein a top end and a bottom end of each of the multiple concrete modules is completely flat;

wherein each of the multiple concrete modules has tapered edges on exactly two edges of the multiple concrete modules;

wherein each of the tapered edges of the multiple concrete modules is one inch wide and is tapered at a 54 degree angle on a backside of each of the multiple concrete modules;

wherein each of the multiple concrete modules include a notch for board fencing;

wherein each of the multiple concrete modules include exactly four horizontal holes that are located within an area of the notch on a front side of each of the multiple concrete modules configured to attach lumber with concrete fasteners; and

wherein the notch on the front side of each of the multiple concrete modules extends upwardly to a top of each of the multiple concrete modules.

2. A method of constructing a stackable concrete post comprising:

placing a concrete pylon base directly into a hole in earth, and securing the concrete pylon base in the hole with earth fill;

wherein the concrete pylon base has two tapered edges from top to bottom, with the bottom of the concrete pylon base wider than the top of the concrete pylon base;

wherein the concrete pylon base has two tapered edges from one side of the top of the concrete pylon base to another side of the top of the concrete pylon base;

wherein the concrete pylon base has a galvanized wire cage within the concrete pylon base;

wherein the galvanized wire cage within the concrete pylon base is made of 16 gauge wire and is a one inch by one inch galvanized wire cage;

stacking vertically multiple concrete modules on top of the concrete pylon base;

wherein the concrete pylon base is placed into the hole in the earth with a first module stacked vertically on top

of the concrete pylon base in the hole in the earth secured together with two $\frac{3}{8}$ inch rebars in two $\frac{3}{4}$ inch diameter holes filled by anchoring cement;

wherein the multiple concrete modules include exactly two $\frac{3}{4}$ inch diameter by 9 inch length holes within each of the multiple concrete modules for rebar;

placing a single rebar inserted within each of the two $\frac{3}{4}$ inch diameter by 9 inch length holes within each of the multiple concrete modules, wherein each of the single rebar extends from a top one of the multiple concrete modules into the concrete pylon base;

wherein each of the exactly two $\frac{3}{4}$ inch diameter by 9 inch length holes are vertical holes;

wherein each of the exactly two $\frac{3}{4}$ inch diameter by 9 inch length holes are two inches from each other and $2\frac{1}{2}$ inches from a side of each of the multiple concrete modules;

wherein each of the multiple concrete modules, other than the concrete pylon base, are of equal size;

placing anchoring cement within the $\frac{3}{4}$ inch diameter by 9 inch length holes within each of the multiple concrete modules;

placing waterproof silicone between one of the multiple concrete modules and another one of the multiple concrete modules;

wherein the multiple concrete modules are reinforced with a galvanized wire cage inside each of the multiple concrete modules;

wherein the galvanized wire cage inside each of the multiple concrete modules is a 16 gauge one inch by one inch wire cage;

wherein each of the multiple concrete modules has tapered edges on exactly two edges of the multiple concrete modules,

wherein each of the tapered edges of the multiple concrete modules is one inch wide and is tapered at a 54 degree angle on a backside of each of the multiple concrete modules;

wherein each of the multiple concrete modules include a notch for board fencing;

wherein each of the multiple concrete modules include exactly four horizontal holes that are located within an area of the notch; and

wherein the notch extends upwardly to a top of each of the multiple concrete modules; and connecting the multiple concrete modules to board fencing with drop-in anchors and concrete fasteners.
